US00D487266S

(12) **United States Design Patent** (10) Patent No.: **US D487,266 S**
Morimiya (45) Date of Patent: ** Mar. 2, 2004

(54) **MACHINE FOR IDENTIFYING FINGERPRINTS**

JP 1100843 S 2/2001
JP 1147351 S 7/2002

(75) Inventor: **Yuji Morimiya**, Tokyo (JP)

(73) Assignee: **Sony Corporation**, Tokyo (JP)

(**) Term: **14 Years**

(21) Appl. No.: **29/164,420**

(22) Filed: **Jul. 25, 2002**

(51) LOC (7) Cl. **14-02**

(52) U.S. Cl. **D14/384**

(57) **CLAIM**

The ornamental design for a machine for identifying fingerprints, as shown and described.

DESCRIPTION

FIG. 1 is a perspective view of a machine for identifying fingerprints showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

Portions in broken lines in FIGS. 1-5 are for illustrative purposes only and form no part of claimed design.
